UNITED STATES PATENT OFFICE.

JOHN A. THOMAS, OF COLUMBUS, OHIO, ASSIGNOR TO THE J. A. THOMAS COMPANY, OF COLUMBUS, OHIO, A CORPORATION OF OHIO.

FIRE-FIGHTING APPARATUS.

1,324,572.

Specification of Letters Patent.

Patented Dec. 9, 1919.

Application filed September 24, 1917. Serial No. 192,910.

To all whom it may concern:

Be it known that I, JOHN A. THOMAS, a citizen of the United States, residing at Columbus, in the county of Franklin and State 5 of Ohio, have invented certain new and useful Improvements in Fire-Fighting Apparatus, of which the following is a specification.

This invention relates to fire fighting apparatus and has particular reference to that 10 type of apparatus employing a chemicalized stream for extinguishing a fire. Specifically, my invention is an improvement over the structure claimed in my Patent No. 1,152,452, issued September 7, 1915.

15 In the present invention, I have aimed to arrange the parts in a more compact form, in order that considerable less space will be utilized in mounting the same upon a mobile truck.

20 The present invention also has for its object, the introduction of water into the mixing chamber from a point on the discharge side of the pump, this being accomplished by means of a valved conduit, the chamber 25 end of the conduit being provided with an ejecting nozzle having a plurality of opposed jets, one of which ejects the fluid into the underlying chamber and the other jet extends upwardly, whereby the liquid forced 30 out of the upper jet will revolve a conveyer, to discharge a suitable quantity of a powdered chemical into said chamber.

A further object is to provide the mixing chamber with automatically operating mechanism so situated that when the chamber becomes filled to a pre-determined level, the mechanism will be operated to shut off the supply of fluid to said chamber.

35 A still further object is to provide apparatus of this character wherein the mechanism employed is of a purely automatic character, reliable in operation and not likely to become out of order.

The preferred embodiment of my invention is shown in the accompanying sheet of drawing, in which similar characters of reference describe corresponding parts, and in which:

40 Figure 1 is a central vertical section shown somewhat diagrammatically of the pump and the mixing chamber in their proper relation.

Fig. 2 is a horizontal sectional view, taken along the line 2—2 of Fig. 1.

Referring more particularly to the drawing, the pump A comprises a casing 1 having a plurality of inlet pipes 2 communicating therewith and disposed in any desired manner. The casing is so formed interiorly that a passageway 3 is provided therein leading 45 from the inlet pipes 2, said passageway being connected by an opening 3^a with the rotor chamber of the pump and situated within said chamber are two rotor members 5. These rotor members are mounted upon 50 shafts 6 and one of them is driven in any desired manner and from any source of power, the rotors thus intermeshing so that one drives the other. The wall 7 in connection with which these rotors operate, are of a 55 size and shape to closely fit the projecting teeth of the rotor, so that pockets 8 are formed in which the water is forced around said rotors and ejected through the discharge opening 9. At this point, the discharge 60 connecting element 10 is attached, said element being utilized to convey the water to a hose or any other element of use.

65 Directly above the discharge point 9, there is provided a by-pass pipe 11, in the form of 70 a valved conduit and in which is interposed a hand controlled valve 12 and a float actuated valve 13. This conduit leads and discharges its contents into the chemical mixture container 14, by providing the container 75 end of the conduit with an ejecting nozzle 15, said nozzle being provided with vertically opposed jets 16 and 17. Thus it will be seen that when the pump is in a state of 80 operation, a fluid will be forced through the conduit 11, when the valves 12 and 13 are open, and discharged by means of the nozzle 15 into the container 14.

85 In order to feed a chemical such as sodium bicarbonate in proper proportions to the 90 container, use is made of a casing 18 into which the conduit 11 extends, and secured to the upper end of the casing is the lower funnel shaped discharge end 19 of a chemical 95 containing hopper 20. The end 19 of the 100 hopper has rotatably mounted therein a screw conveyer 21, which has a shaft 22 thereof extended to receive a spiral 23, the latter being located within a housing 24 rig-

idly mounted within the casing 18. Thus it will be evident that the fluid discharged from the jet 16 will strike against the spiral 23 and will thereby cause the rotation of the 5 shaft 22 and its associate feed conveyer 21, so that a suitable quantity of chemical contained within the hopper 20 will be automatically introduced into the container 14. A damper door 25 is rotatably mounted 10 within the discharge end of the screw conveyer housing and is provided with openings adapted to register with similar openings formed in the webbed extremity 26 of said discharge end 19, whereby upon rotating the 15 damper member 25, the extent of said openings may be readily adjusted to govern the flow of the chemical therethrough.

Water ejected from the nozzle end 17 is forced into the container 14, whence it is 20 mixed with the chemical from the hopper 20, and when the chemicalized fluid within the container reaches a pre-determined level, the flow of fluid thereto is automatically cut off. This is accomplished through the 25 provision of the valve 13 in the conduit 11 which has the stem 27 thereof provided with an operating link 28, to the end of which is suitably secured a ball member 29, said stem operating through an opening 30 provided in 30 the top 31 of the container 14, the ball member 29 being thus positioned within the container. Thus when the fluid arises to a point near the top 31, the stem 37 will be elevated by the ball member 29, so that the 35 internal mechanism (not shown) of the valve 13 will be actuated to obstruct the flow of fluid through said conduit, as will be clearly understood.

Leading from the lower end of the 40 container 14 is a lower valved conduit 32, which is provided with a manually operated valve 33 and with a check valve 34, the latter permitting fluid to flow but one way through the conduit 32. The end of said conduit 45 terminates within a casing 35 and leading from said casing is a discharge nozzle 36, which projects into the pump casing and terminates within the opening 3^a, whereby the 50 contents of the container 14 will be discharged in a position to be caught by the rotors 5 and thoroughly mixed with the outgoing fluid. Formed in the casing 35 is a nozzle element 38 which communicates with the pipe 39 extending from the conduit 11 55 and which has a valve 40 provided therein. It will be seen that fluid will be discharged under considerable pressure from the ejecting element 38, into the nozzle 36 and this action will create a suction so as to facilitate 60 the flow of fluid from the container 14 to the nozzle 36.

From the foregoing description, it will be apparent that I have provided a type of fire fighting apparatus wherein the proper proportions between the chemical and water

have been automatically secured, and in an apparatus wherein the several parts thereof are automatically controlled. In operation, when the rotors 5 are in a state of rotation, water will be drawn from the inlet pipes 70 through the pump and discharged into the connection 10 and into the conduit 11.

Water passing through the conduit 11 is discharged into the container 14 but simultaneous with this discharge the feed conveyer 75 21 is operated so that a chemical contained within the hopper 20 will be introduced into the fluid located within the container 14, means being provided in conjunction with the container to shut off the flow of fluid 80 through the conduit when the water within the container 14 reaches a predetermined level. The flow of chemicalized fluid from the container is perfectly accomplished by suction, the same being effected through the 85 provision of the pipe 39 and the ejecting element 38, which creates a suction within the casing structure 35 so as to effectively withdraw the fluid from the container 14 and to eject it under pressure into the pump structure. 90

It will thus be seen that there is provided a device wherein the objects of the present invention have been achieved and that all the advantageous features above mentioned 95 are, among others, present. The apparatus is extremely simple in construction, easy to operate, of few and simple parts and not likely to become out of order. By reason of the automatic features of the apparatus, 100 the same will require practically no attention and will necessitate but a minimum of adjustments.

Having described the invention, what is claimed as new and patentable is:

1. In a fire fighting apparatus, the combination with a force pump and a mixture container, of a conduit leading from the discharge side of said pump into said container, a second conduit leading from the bottom of 110 said container to said pump, a regulating valve in said first mentioned conduit, means connected with said valve and situated within said container, whereby when the fluid within said container reaches a pre-determined level, the flow of fluid through the 115 conduit will be prevented.

2. In a fire fighting apparatus, the combination with a source of water supply and a mixture container, of a conduit leading 120 from said source into said container, a second conduit leading from the bottom of said container back to said water source, a regulating valve in one of said conduits, and a branch conduit communicating with said former conduits and provided with means operable to create a suction within said second conduit to facilitate the flow of fluid from said container to said source. 125

3. In a fire fighting apparatus, the combi- 130

nation with a force pump and a mixture container, of a conduit leading from the discharge side of said pump into said container, a second conduit leading from the 5 bottom of said container back to said pump, a chemical containing hopper communicating with said container, a conveyer situated within the discharge end of said hopper, and a nozzle carried by the container end of said

first named conduit and disposed to rotate 10 said conveyer upon the flow of fluid through said conduit.

In testimony whereof I affix my signature in presence of two witnesses.

JOHN A. THOMAS.
